SKIN CLEANING COMPOSITION

Leonard L. McKinney and John C. Cowan, Peoria,
Ill., assignors to the United States of America
as represented by the Secretary of Agriculture

No Drawing. Application October 11, 1949,
Serial No. 120,807

2 Claims. (Cl. 252—130)

(Granted under the act of March 3, 1883, as
amended April 30, 1928; 370 U. S. G. 757)

1

This application is made under the act of March 3, 1883, as amended by the act of April 30, 1928, and the invention herein described, if patented in any country, may be manufactured and used by or for the Government of the United States of America for governmental purposes throughout the world without the payment to us of any royalty thereon.

This invention relates to cleaning compositions and, more particularly, to skin cleaning compositions containing detergent and emulsifying ingredients together with a mild abrasive or rubbing agent.

Among the objects of this invention is the provision of a novel and improved skin cleaning composition containing as mild abrasive a chemically treated residue obtained as a byproduct in the extraction of oil, proteins and other products from soybeans. Another object is to provide an abrasive-containing cleaning composition from soybean residue which does not leave a sticky glue-like film on the skin after use, and any residue left in wash basins, drains, etc., does not putrefy or ferment. Still another object of the invention is to provide an abrasive agent for cleaning compositions from soybean residue which does not tend to dissolve in mildly alkaline aqueous media.

Soybean meal from which the oil has been removed contains a considerable quantity of protein which is usually recovered by extraction with alkali or acid solvents leaving a residue having a greatly reduced protein content which contains a relatively large proportion of crude fiber and other relatively inactive constituents. This material is of little value in feeds and is in general a byproduct of low value.

This residue has been suggested as an ingredient in hand soaps as a substitute for the usual mineral or organic abrasives ordinarily found in such cleaners. Heretofore, however, cleaning compositions containing the residue have been relatively unsatisfactory since they dissolve somewhat in the wet soap mixture, have relatively poor abrasiveness when soaked in water and leave the hands sticky as if a film of glue were present.

It has been found that these disadvantages of such prior cleaning compositions have been largely due to the residual protein remaining after alkali or acid extraction. This residual protein usually amounts to 20 to 30 percent by weight of the residue, and under the strongly solvent action of the aqueous media present during cleaning operations tends to dissolve or disperse. As a result a film is deposited upon the

skin which is difficultly soluble in water and hence cannot easily be removed by rinsing. Moreover, partial dispersion of the protein tends to soften the residue to such an extent that its abrasive qualities are materially reduced, and the residue itself rendered undesirably sticky. As a consequence it tends to adhere to crevices in the wash bowl and other fittings where it remains to putrefy or ferment, causing disagreeable odors.

10 In accordance with this invention the soybean residue is treated with formaldehyde, rendering the residual protein substantially insoluble and undispersable even during the strong solvent conditions of use. The particles of residue thus treated do not soften to the point of semi-solution but remain as discrete particles possessing mild abrasive properties. Moreover, no undesirable film is left on the skin after use. The abrasive particles, although somewhat softened and swelled have a greatly reduced tendency to adhere to the wash bowl or drains. Even those particles which might become lodged in crevices have no tendency to putrefy or ferment. Furthermore, the swelled particles tend to adsorb grease and dirt facilitating removal from the hands. Bars or cakes comprising our mild abrasive possess an excellent shelf life.

Obviously, this invention may be applied to whole soybean meal in which the oil has been removed, but the high-grade protein content of this original meal is of considerable value in other uses. For this reason the residual meal is greatly preferred in this invention. In either case, the formaldehyde treatment hardens the protein and renders it insoluble thus greatly improving the material as an ingredient in cleaning compositions. The formaldehyde treated residue is light tan in color and when ground to 20/60 mesh weighs 0.7-0.8 gram per cubic centimeter.

In carrying out the invention the formaldehyde-treated residual soybean meal may be ground to pass a screen of the desired size, for example 20 mesh or finer. It is then mixed with surface active material such as detergent or emulsifying ingredients which may be carbonates, borates or phosphates of the alkali metals, fatty acid soaps, and the like. The composition may take the form of a powder, paste, or cake as desired, the details of the preparation of each being well-known in the art. For example, the mixed powder may be moistened to the desired consistency to form a paste, or binders added, if desired, and the powder may be subjected to pressure and thus molded into cake form. The vari-

ous emulsifying and detergent ingredients may be used singly or in any desired combination.

In general, the formaldehyde-treated residual soybean meal should comprise 30 to 60 percent of the total composition, about 40 percent being preferred.

The formaldehyde treatment of the residue may be carried out in any of a variety of simple ways. For example, the moist residue from the protein extraction step may be conveyed to a heated chamber and subjected therein to formaldehyde vapors. The moist treated meal may then be dried directly, care being taken that excess formaldehyde be substantially removed from the treated residue before discharge.

Alternatively, the residue in the moist or dry condition may be treated with formalin solution and dried in a warm oven. In the latter method about 10 ml. of 40 percent formalin may be added to 100 g. of moist residue. The proportion of formaldehyde to residue may vary over a wide range. It is merely necessary that the protein content of the residue be subjected to the formaldehyde in any of a variety of known ways and the excess formaldehyde removed either by washing the treated residue or by heating it for a short period to drive off excess formaldehyde vapors.

The following specific examples illustrate the invention. Parts are by weight unless otherwise specified.

Example 1

Two parts by weight of a commercial powdered fatty acid soap containing minor amounts of mineral detergents are mixed with one part of formaldehyde-treated soybean residue. The mixture was ground and mixed thoroughly in a mortar and pestle. The powder was then used as a hand soap. It possessed excellent abrasiveness and compared favorably with similar compositions containing more expensive abrasive ingredients. It was free of formaldehyde odor. A sample was placed in water, and a Kjeldahl analysis revealed the absence of nitrogen in the supernatant soap solution after one hour of stirring. The filtered moist residue failed to show signs of putrefaction after several weeks.

Example 2

The powdered mixture prepared as in Example 1 was compressed into a test cake. It was used for a plurality of hand washings and found to possess excellent abrasive and cleaning properties. The individual abrasive particles remained intact and showed no tendency to slip or leave the cake without the exertion of some mechanical

force. After washing and rinsing the hands, no disagreeable sticky film remained and the loosened particles were mobile in the wash water and easily flushed away. After several months standing in the open air with occasional usage, the test cake exhibited no tendency toward discoloration or disintegration and developed no disagreeable odor. Throughout this time the desirable cleansing properties of the cake remained unchanged.

In the above examples the proportions may be varied considerably, the preferred range of abrasive content being about 40 percent by weight. The treated residue is readily compatible with

any of the commonly used detergents or emulsifying agents, such as for example, trisodium phosphate, washing soda, borax, lauryl sulfate, coconut oil soap, and other alkali metal soaps. Such compositions show no tendency toward deterioration upon standing for periods as long as one year.

We claim:

1. A composition for cleaning the skin comprising from about 30% to 60%, by weight, of formaldehyde-treated dried meal comprising residual protein, said meal having been obtained as a byproduct from the extraction of oil and other material from soybean and being of a particle size not substantially greater than 20 mesh, and from about 40% to 70%, by weight, of a fatty acid soap.

2. A skin-cleaning composition in cake form comprising from about 30% to 60%, by weight, of formaldehyde-treated dried meal comprising residual protein, said meal having been obtained as a byproduct from the extraction of oil and other material from soybean and being of a particle size not substantially greater than 20 mesh, and from about 40% to 70%, by weight, of a fatty acid soap.
